UNITED STATES PATENT OFFICE.

HARRY M. PFLAGER, OF ST. LOUIS, MISSOURI, ASSIGNOR TO DOUBLE BODY BOLSTER COMPANY, OF ST. LOUIS, MISSOURI, A CORPORATION OF NEW JERSEY.

CAR END FRAME.

1,048,997.

Specification of Letters Patent. Patented Dec. 31, 1912.

Application filed April 9, 1912. Serial No. 689,568.

To all whom it may concern:

Be it known that I, HARRY M. PFLAGER, a citizen of the United States, residing at the city of St. Louis, State of Missouri, have 5 invented a certain new and useful Improvement in Car End Frames, of which the following is a full, clear, and exact description, such as will enable others skilled in the art to which it appertains to make and use the 10 same, reference being had to the accompanying drawings, forming part of this specification, in which—

Figure 1 is a vertical section taken transversely through the platform portion of a 15 car underframe, and showing an end frame of my improved construction in elevation. Fig. 2 is a plan view of the end frame. Fig. 3 is a side elevation of the end frame. Fig. 4 is a vertical section taken on the line 4—4 20 of Fig. 1. Fig. 5 is a horizontal section taken approximately on the line 5—5 of Fig. 1.

This invention relates generally to railway car construction and more particularly 25 to cast metal end frames for cars of the type disclosed in Patent No. 917,716, issued April 6th, 1909, and No. 929,705, issued August 3d, 1909.

One of the most important features in the 30 construction of the present forms of railway cars, and particularly those cars utilized for transporting passengers, is the reinforcing of the ends of the cars so as to provide an exceptionally strong, rigid construction which will effectually resist crushing stresses delivered to the ends of the cars, consequently overcoming the tendency 35 of the cars to telescope in case of collisions, and affording the greatest possible degree of 40 safety to the occupants of the cars.

My improvement contemplates a comparatively light weight, strong and durable one-piece cast metal structure which is formed and braced so as to effectually resist end shocks and crushing stresses imparted to the ends of the car, thereby providing a construction which is anti-telescopic in effect.

The principal objects of my present invention are to generally improve the construction of the cast metal end frames disclosed in the patents above referred to, to 50 form braces on the end frame and fix said braces to the under frame in such a manner

as to rigidly maintain said end frame in an 55 upright position, and further to arrange and dispose the various uprights, cross pieces and braces forming the end frame so as to utilize to the greatest possible advantage the strength of the material of which said 60 parts are formed in resisting end shocks and crushing stresses due to collisions.

To the above purposes my invention consists in certain novel features of construction and arrangement of parts hereinafter 65 more fully described and claimed.

Referring by numerals to the accompanying drawings, 1 designates the under frame, 2 the end sill thereof and 3 the platform casting, all of which parts are preferably 70 cast integral. My improved frame as shown includes a pair of upright members 4 which perform the function of door posts, a pair of side members or posts 5 which perform the function of corner posts and a pair of 75 intermediate upright members or posts 6. All of these posts are preferably channel shape in cross section, although other cross sectional shapes may be utilized, if desired.

The lower portions of the corner posts 5 and intermediate posts 6 are united by web plates 7 and the lower portions of the intermediate posts or door posts 4 are united by integral web plates 8 which are cut away as designated by 9 immediately adjacent the 80 lower ends of the door posts 4 in order to accommodate the side rails or members 3^a of the platform casting. Formed integral with the lower portions of the door posts 4 and projecting inwardly therefrom are web 85 plates 10. Formed integral with the upper portions of all of the web plates 7, 8 and 10 and projecting rearwardly therefrom is a horizontally disposed plate 11 which is continuous from one corner post 5 to the other 90 and when the end frame is applied to the under frame, this plate 11 rests directly upon top of the end member of said under frame and is rigidly fixed thereto by means of rivets 12 or like fastening devices. Rivets 13 or like fastening devices are utilized 95 for rigidly fixing the web plates 7, 8 and 10 to the front wall of the end member of the under frame.

In order to brace and strengthen the door 105 posts 4, the lower portions thereof are gradually widened to their lower ends to form brackets 14, the lower ends of which

extend entirely across the horizontally disposed plate 11. Formed integral with the lower portion of each corner post 5 is a rearwardly extending bracket or heel portion 15, the under side of which rests directly upon the corresponding side rail of the under frame. The horizontally disposed base flanges 15^a of these brackets are rigidly fixed to the under frame by means 5 of rivets 16 or like fastening devices and the rear ends of said brackets bear directly against shoulders 17, which latter are formed on the side rails of the under frame. 10

By the construction just described, the 15 lower portion of the cast metal end frame is rigidly fixed to the under frame and all end shocks or crushing stresses imparted to said end frame are effectually resisted by the bearing of the lower ends of the posts 20 or uprights against the front side of the end sill and by the engagement of the rear ends of the brackets 15 against the shoulders 17. Such construction takes the shearing strain off the rivets utilized in fixing the 25 end frame to the under frame and any strains or shocks imparted to the upper portion of the end frame and which may tend to swing the upper portion of said frame inwardly will be resisted by the bearing of the brackets 15 directly upon top of the 30 under frame.

The upper portions of the uprights 4, 5 and 6 are united by a horizontally disposed plate 18 which performs the function of a 35 lintel for the door frame, said plate being widest at its central portion and gradually tapering toward its ends. Formed integral with the rear portion of the plate 18 and projecting upwardly therefrom at points 40 adjacent to the upper ends of the intermediate posts 6 are vertically disposed web plates 19 and formed integral with the rear edge of the plate 18 and projecting upwardly therefrom between these web plates 45 19 is a vertically disposed plate 20. The end portions of this plate 20 are widened and provided with openings 21 which are for the purpose of accommodating the bell cords of the train. Formed integral with 50 the plates 18 and 20, at points inside the plates 19, are webs or plates 22 which are for the purpose of attaching parts of the hood supporting frame work. Brackets 23 are formed integral with the plates 19 and 55 the outer portions of the plate 18, and the inner ends of these brackets and the upper ends of the plates 19 serve as supports for the lower portion of the ventilator frame. The side plates 24 of the car body frame rest 60 directly on top of the uprights or posts 5 and where these plates are in the form of channels, as shown, the upper outer corners of the posts or uprights 5 are cut away as designated by 25 to accommodate the outer 65 flanges of said channels.

My improved end frame is cast in a single piece and therefore can be readily applied to a car under frame and body, and by the use of such an end frame considerable time and labor can be saved in the assembling or building up of a car body. The 70 end frame is rigidly fixed to the under frame by means of rivets and the construction of the lower portion of the end frame is such that when the same is applied to the under frame, all shearing stresses are taken off the rivets utilized in fastening the parts to one another. By providing the rearwardly projecting brackets at the sides of the end frame and arranging the same so as to bear directly upon the under frame, an exceptionally strong, rigid anti-telescoping construction is provided which affords a maximum degree of safety to the occupants of the car during collisions. 75

Ordinarily the greatest force of end shocks and crushing stresses occurring during collisions is developed at or below the belt rail of the car and for this reason it is especially desirable that the lower portion 80 of the end frame be substantially braced and fixed to the under frame so as to resist to the greatest extent the force of the blows and stresses resulting from collisions. For this reason, I provide the brackets extending 85 rearwardly from the corner posts and unite the lower ends of all of the posts with the webs which bear directly against and are attached to the end sill of the under frame. 90

It will be readily understood that minor 95 changes in the size, form and construction of the various parts of my improved end frame can be made and substituted for those herein shown and described without departing from the spirit of my invention, the 100 scope of which is set forth in the accompanying claims. 105

I claim:

1. The herein described end frame for car bodies comprising a series of upright members, vertically disposed web plates integral with the lower portions of said uprights, a horizontally disposed plate integral with and projecting rearwardly from the web plates, rearwardly projecting brackets on the lower portions of the outer pair of uprights, a member connecting the upper portions of all of the uprights, and brackets on said last mentioned member, which brackets serve as points of attachment for parts of the car hood supporting frame. 110 115

2. The herein described end frame for cars comprising a pair of door posts, a pair of corner posts, a pair of intermediate posts, web plates integral with the lower portions 120 of said posts, a horizontally disposed plate integral with and projecting rearwardly from the upper portions of said web plates, a horizontally disposed member integral 125 with and connecting the upper portions of 130

all of the posts, and car hood frame, attaching brackets integral with said horizontally disposed member.

3. The combination with a car under frame, of an end frame comprising a series of uprights, the lower ends of which bear against the face of the end member of the under frame, web plates integral with the lower portions of the uprights which web plates bear against and are fixed to the end member of the under frame, a horizontally disposed plate integral with the upper portions of the web plates bearing upon the end member of the under frame, and brackets integral with and projecting rearwardly from the corner posts which brackets bear upon and are fixed to the under frame, a horizontally disposed plate integral with and connecting the upper portion of all of the posts, and hood supporting frame attaching brackets formed integral with said last mentioned plate.

4. The herein described cast metal end frame comprising a series of uprights, web plates integral with the lower portions of said uprights, a plate connecting the upper portions of the uprights, a vertically disposed web plate integral with said plate which vertically disposed web plate is provided with openings adapted to receive the train bell cord, and hood supporting frame attaching brackets integral with the two last mentioned plates.

5. A cast metal end frame for car bodies comprising a series of uprights, web plates connecting the lower portions of said uprights, a lintel plate integral with the upper portions of said uprights, a pair of vertically disposed plates integral with said lintel plate, the upper portions of which vertically disposed plates are adapted to receive the ventilator framing of the car body, hood frame attaching brackets integral with said lintel plate, a web plate integral with the lintel plate between the vertically disposed plates, and which web plate is provided with openings adapted to receive the train bell cords.

6. The herein described cast metal end frame for cars comprising a series of uprights, web plates connecting the lower portions of said uprights, a lintel plate connecting the upper portions of said uprights, a vertically disposed plate integral with said lintel plate, brackets integral with the end portions of the lintel plate, which brackets form supports for the ventilator frame, and hood frame attaching brackets integral with the lintel plate and vertically disposed plate.

In testimony whereof I hereunto affix my signature in the presence of two witnesses, this 2nd day of April, 1912.

HARRY M. PFLAGER.
